UNITED STATES PATENT OFFICE.

EMIL G. SAUER, OF RICHMOND HILL, NEW YORK, ASSIGNOR TO THE BIGELOW CARPET COMPANY, A CORPORATION OF MASSACHUSETTS.

DESIGN FOR A RUG.

No. 39,783.

Specification for Design.

Patented Jan. 19, 1909.

Application filed October 9, 1908. Serial No. 457,023. Term of patent 3½ years.

To all whom it may concern:

Be it known that I, EMIL G. SAUER, a citizen of the United States, residing at Richmond Hill, in the county of Queens and State of New York, have invented a new, original, and ornamental Design for a Rug, of which the following is a specification, reference being had to the accompanying drawing, forming part thereof.

The design, as shown in the drawing, consists in a new design for a rug, one quarter of the full design being shown in the drawing.

The design comprises a central medallion placed upon a ground work, a corner piece and a border, as shown in the drawing.

I claim:

The ornamental design for a rug, as shown.
